UNITED STATES PATENT OFFICE.

ANGUS LEO CAMPBELL, OF NORTH SYDNEY, NOVA SCOTIA, CANADA.

COMBINATION ENVELOP AND MUSIC-SHEET.

1,243,037.

Specification of Letters Patent. Patented Oct. 16, 1917.

Application filed August 7, 1916. Serial No. 113,646.

To all whom it may concern:

Be it known that I, ANGUS LEO CAMPBELL, a subject of the King of Great Britain, and resident of North Sydney, in the Province of Nova Scotia, Dominion of Canada, have invented certain new and useful Improvements in Combination Envelops and Music-Sheets, of which the following is the specification.

10 This invention relates to improvements in combination envelops and music sheets particularly adapted to be utilized with gramophone disk records, and the objects of the invention are to permit of the player readily recognizing the song or piece of music being played by a gramophone, to render the music sheet capable of being utilized as the envelop flap and generally to adapt the envelop to better perform the functions required of it.

15 With the above and other objects in view the invention consists essentially of the improved construction particularly described and set forth in the following specification and accompanying drawing forming part 20 of the same.

In the drawing,

Figure 1 is a front elevation of the envelop with the music sheet open.

Fig. 2 is a back elevation of the envelop with the music sheet open.

Like characters of reference refer to like parts in the several figures.

Referring to the drawings, A represents the improved envelop comprising the receptacle 10 in which the disk record of a gramophone is housed, the inner wall of the receptacle being provided with a V-shaped notch 12 to facilitate in withdrawing the record.

The flap 13 of the envelop may be formed integral with the receptacle or it may be attached by an adhesive if so desired, the

said flap being substantially in the form of a music sheet having the music and words of the song on the inner face while the outer face may as in the embodiment illustrated 45 set forth the chorus or continuation of a piece of music.

The outer wall 14 of the receptacle 10 may have the title together with the name of the artist rendering the music. 50

It is well known that in playing a gramophone record for the first time, considerable difficulty is experienced in catching the words of the song, so that by utilizing an envelop of this description the player may 55 readily follow the music being rendered.

As many changes could be made in the above construction and many apparently widely different embodiments of my invention, within the scope of the claim, constructed without departing from the spirit or scope thereof, it is intended that all matter contained in the accompanying specification and drawing shall be interpreted as 60 illustrative and not in a limiting sense. 65

What I claim as my invention is:

Means provided with records of the same music in different forms, one form comprising ordinary printed music notation permanently carried on said means, and the other, 70 a gramophone music disk record detachably carried by said means, the ordinary printed music notation being so located and arranged on the means that it may be used as sheet music for any of its ordinary uses and coincidentally with the use of the disk record. 75

In witness whereof I have hereunto set my hand in the presence of two witnesses,

ANGUS LEO CAMPBELL.

Witnesses:

RUSSEL S. SMART,
B. LEAMY.
